UNITED STATES PATENT OFFICE

MURRAY LESSER, OF BROOKLYN, NEW YORK

DESIGN FOR A DISPLAY BOX

Application filed August 29, 1930. Serial No. 36,818. Term of patent 7 years.

To all whom it may concern:

Be it known that I, MURRAY LESSER, a citizen of the United States, and a resident of New York city, borough of Brooklyn, in the county of Kings and State of New York, have invented the new, original, and ornamental Design for a Display Box, of which the following is a specification.

Reference is had to the accompanying drawing, forming part thereof, wherein—

Figure 1 is a perspective view of a display box showing my new design, the same being illustrated with the cover open;

I claim—

The ornamental design for a display box substantially as shown and described.

MURRAY LESSER.
